T. BURNS

CULTIVATOR ATTACHMENT

Filed Oct. 18. 1922

Mr. May. Durall,
E. Yeager

WITNESSES

Theodore Burns,

INVENTOR

BY *Victor J. Evans*

ATTORNEY

UNITED STATES PATENT OFFICE.

THEODORE BURNS, OF CLAYTON, INDIANA.

CULTIVATOR ATTACHMENT.

Application filed October 18, 1922. Serial No. 595,310.

To all whom it may concern:

Be it known that I, THEODORE BURNS, a citizen of the United States, residing at Clayton, in the county of Hendricks and State of Indiana, have invented new and useful Improvements in Cultivator Attachments, of which the following is a specification.

This invention relates to cultivator attachments, in the nature of a leveller, made up of two identically constructed relatively adjustable members, between which a plurality of teeth are supported, in the manner to permit the teeth to be spaced different distances apart, the attachment in its entirety being adjustable to accommodate itself to any type of cultivator.

The nature and advantages of the invention will be better understood when the following detailed description is read in connection with the accompanying drawing, the invention residing in the construction, combination, and arrangement of parts as claimed.

In the drawing forming part of this application, like numerals of reference indicate similar parts in the several views, and wherein:

Figure 1 is a fragmentary view of a cultivator, showing the attachment associated therewith.

Figure 2 is a detailed view of one of the members of the attachment.

Figure 3 is a sectional view taken on line 3—3 of Figure 1.

Figure 4 is a fragmentary view, showing the use of the bracing element.

Figure 5 is a sectional view taken on line 5—5 of Figure 4.

Figure 6 is a view somewhat similar to Figure 3, showing the use of the bracing element.

Figure 7 is a detail view of the bracing element.

Figure 8 is a plan view of Figure 6.

The attachment forming the subject matter of the invention comprises two bars indicated at 10 and 11 respectively, and these bars are arranged in spaced parallel relation as shown. Each bar has one end extended to provide a vertically disposed portion 12, the latter terminating to provide an attaching portion 13 which is secured to the cultivator by means of U-bolts 14 which straddle said parts, and held associated therewith by means of a plate 15, which re-

ceives the ends of the U-bolts, which ends also accommodate nuts 16. The bars 10 and 11 are adjustable longitudinally with respect to each other, so that the attachment can be varied in size to accommodate itself to any make of cultivator. Arranged between the bars 10 and 11 are teeth 17 which are held in position by means of U-bolts 18 which straddle the parts in the manner illustrated in Figure 3. Each of these bolts have associated therewith a plate 20 and nuts 21, and which when tightened hold the parts fixed relatively. It is manifest that when the size of the attachment is varied, incident to the longitudinal adjustment of the bars 10 and 11, that the teeth may also be spaced different distances apart, and the distance between the teeth may also be varied without changing the size of the attachment. With the attachment associated with the cultivator it is particularly useful in the capacity of a leveller and pulverizer.

In Figures 4 to 8 inclusive, I have illustrated the use of a reinforcing or bracing element which is designed to prevent turning, or relative movement of the teeth with respect to the bars 10 and 11 respectively. This element is clearly shown in Figure 7 and consists of an elongated plate 22 from the diagonal corners of which project lugs or fingers 23. This plate is arranged at one side of the adjacent bar 11 as shown in Figure 4, and arranged parallel with the tooth 17. The lugs or fingers 23 are arranged above and below the longitudinal edges of the bar 11 extending in the same direction, and also arranged at the opposite sides of the tooth 17. This construction prevents the tooth from turning or twisting, and in fact, eliminates all lateral movement of the tooth with respect to the parallel bars. The plate 22 is held in proper position by means of the U-bolts 18.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:

1. A cultivator attachment of the character described comprising a pair of spaced parallel bars, one end of each bar being extended to provide a vertically disposed por-

tion, offset to be attached to the cultivator, said bars being susceptible of longitudinal adjustment relatively, and teeth supported by said attachment and projecting below 5 said bars.

2. A cultivator attachment of the character described comprising spaced parallel bars, one end of each bar being extended to provide a vertically disposed portion and

having an offset extremity, means for clamping said offset extremity to the cultivator, teeth arranged between the said spaced bars and capable of being arranged different distances apart, and means for clamping the teeth and bars together to hold the parts 10 15 fixed relatively.

In testimony whereof I affix my signature.
THEODORE BURNS.
